UNITED STATES PATENT OFFICE.

CHARLES A. GELIN, OF CHICAGO, ILLINOIS, ASSIGNOR TO W. CARY LEWIS, OF CHICAGO, ILLINOIS.

JOURNAL PACKING.

1,423,207.

Specification of Letters Patent.

Patented July 18, 1922.

No Drawing.

Application filed May 10, 1920. Serial No. 380,191.

To all whom it may concern:

Be it known that I, CHARLES A. GELIN, a citizen of the United States, residing at Chicago, in the county of Cook and State 5 of Illinois, have invented certain new and useful Improvements in a Journal Packing, of which the following is a description.

My invention belongs to that general class of products known as a journal or like 10 packing, and relates particularly to a packing particularly suited for lubricating purposes, together with the preferred method of manufacturing the packing. The invention has among its objects the production of an 15 efficient, reliable, inexpensive and satisfactory packing which will be extremely durable and satisfactory for use under practically all conditions. Many other objects of the construction herein shown and described 20 will be obvious to those skilled in the art from the disclosures herein given.

To this end my invention consists in the novel product and method herein shown and described, and more particularly pointed out 25 in the claims.

Heretofore, it has been customary to use cotton or wool waste, or a mixture of the two, in journal boxes to carry the oil and apply the same to the journal. However, 30 the cotton and wool waste have a tendency to mat down and become hard, and in time to fail to function properly. The life of the same is comparatively short, although the same may in some cases be removed from the 35 box and cleaned and replaced. However, it quickly mats down again, owing to the weight of the contained oil and lack of resiliency, and consequently may let the journal and bearings run dry. In some instances 40 the cotton and wool waste has been supplemented or replaced by cocoanut fiber, but this product is generally gritty, and it has a tendency to heat, it packs and mats down, consequently its utility and efficiency is not 45 what is should be.

I have found that a very desirable, efficient and inexpensive journal packing can be made by utilizing wood fibers in the form 50 of excelsior, a coarse grade of excelsior being preferred. I also prefer excelsior made from wood which is substantially free from grit or mineral matter embedded in the cell walls. It is well known that certain woods have a tendency to carry up mineral crystals, grit, etc., which become embedded in

the wood cells, the amount varying in different woods. It also is found that the excelsior from some kinds of woods is more resilient and does not break as easily as excelsior made from other woods. I have found that 60 by taking an excelsior made from poplar, basswood and similar woods, a very desirable grade of excelsior for the purpose is obtained. However, generally I prefer to use a wood which, by test, I have found most 65 satisfactory for the particular use for which the packing is to be employed.

In preparing the excelsior for packing purposes, I prefer to have the same as clean and free from dirt, dust and grit as possible, and as before mentioned, in the shape of long and not too fine threads or shavings. If the same is not thoroughly dry, I prefer to dry the same out so as to drive 70 substantially all of the moisture out of the 75 cells and then before the same has had an opportunity to reabsorb moisture from the atmosphere, I prefer to treat the same to the desired extent with an oil or the equivalent which would have more or less of a water- 80 proofing effect and would form substantially a film over the wood, keeping the moisture out. The result is that the excelsior having been dried out, it is apparently much more 85 resiliency or springy than when wet, and the oil does not, to any appreciable extent, seem to affect the resiliency. While, of course, oil is applied to the excelsior when in the journal boxes, this preliminary treatment is generally desirable in order that there may be 90 no moisture accumulated after the drying and before the packing is placed in the journal box.

In some forms of packing, I prefer to combine with the excelsior a mixture of cotton or wool waste, or cotton and wool mixture, the excelsior and waste being thoroughly intermixed so that the various strands or strings of both are intertwined.

Extensive and severe tests have shown 100 that the packing thus produced is far superior to waste alone or to waste and cocoanut fiber or similar packing. It has been found that the wood retains its resiliency for long periods and at all times maintains 105 the waste and packing in contact with the journal, thereby thoroughly lubricating the same. The capillary attraction seems also to be increased, and the wood has a polishing effect on the journal. While I have 110

mentioned the use of a mixture of treated excelsior and waste, this is a matter of preference, as in some cases the treated excelsior alone may be preferred to the mixture.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure 15 by Letters Patent is:

1. A packing of the kind described comprising wood excelsior treated so as to be free from grit and moisture.

2. A packing of the kind described comprising resilient wood excelsior treated so as to be free from moisture.

3. A journal packing of the kind described consisting of a mixture of wood excelsior, treated so as to be substantially free from grit and suitable waste, the same mixed in 25 suitable proportions.

4. A journal packing of the kind described consisting of a mixture of wood excelsior, treated so as to be substantially free from moisture and suitable waste, the same mixed 30 in suitable proportions.

5. A journal packing of the kind described comprising a mixture of treated dried wood excelsior and wool or cotton waste.

6. A journal packing of the kind described 35 comprising a mixture of coarse resilient treated dried wood excelsior and wool or cotton waste.

7. A method of making journal packing consisting in forming wood excelsior from 40 a wood having resilient properties and substantially free from grit, drying the same to remove the moisture, then treating the same with a coating of suitable material repellent to moisture.

8. A method of making journal packing consisting in forming wood excelsior from a wood having resilient properties and substantially free from grit, drying the same to remove the excess moisture, then treating 50 the same with a coating of suitable material repellent to moisture and thence mixing the same with cotton or wool waste in the desired proportion.

In testimony whereof, I have hereunto 55 signed my name in the presence of two subscribing witnesses.

CHARLES A. GELIN.

Witnesses:
